(57) **CLAIM**

The ornamental design for a light bezel for a construction machine, as shown and described.

DESCRIPTION

FIG. 1 is a front perspective view of a light bezel for a construction machine showing our new design;

FIG. 2 is a front perspective view of the light bezel for a construction machine of FIG. 1.

FIG. 3 is a rear perspective view of the light bezel for a construction machine of FIG. 1.

FIG. 4 is a front view of the light bezel for a construction machine of FIG. 1.

FIG. 5 is a rear view of the light bezel for a construction machine of FIG. 1.

FIG. 6 is a left-side view of the light bezel for a construction machine of FIG. 1.

FIG. 7 is a right-side view of the light bezel for a construction machine of FIG. 1.

FIG. 8 is a top view of the light bezel for a construction machine of FIG. 1; and,

FIG. 9 is a bottom view of the light bezel for a construction machine of FIG. 1.

The dashed lines shown in FIG. 1 represent environmental subject matter and form no part of the claimed design.

The dashed lines shown in FIGS. 2-7 and 9 are for illustration only and do not form part of the claimed design.
